UNITED STATES PATENT OFFICE.

CARL FRIEDRICH WILHELM DOEHRING, OF LEIPSIC, GERMANY.

FLUE-CLEANER.

SPECIFICATION forming part of Letters Patent No. 357,309, dated February 8, 1887.

Application filed January 8, 1886. Serial No. 167,968. (No model.)

To all whom it may concern:

Be it known that I, CARL FRIEDRICH WILHELM DOEHRING, of Leipsic, Germany, have invented a new and Improved Flue-Cleaner, 5 of which the following specification is a full, clear, and exact description.

This invention relates to an apparatus for extracting the soot from flues and stove-pipes by means of a device which is connected with 10 one end of the flue and which exhausts the air and soot from the flues.

The invention consists in the details of construction hereinafter more fully pointed out and claimed.

15 In the accompanying drawings, Figure 1 is a section of a building the flue of which is connected with my flue-cleaner. Fig. 2 is a detail horizontal section on line *z z*, Fig. 1. Fig. 3 is an end view of Fig. 2. Fig. 4 is a section on line *T T*, Fig. 3. Fig. 5 is a section on line *S S*, Fig. 3. Fig. 6 is a vertical central section of the flue-cleaner on line *U U*, Fig. 8. Fig. 7 is a top view, partly in section, of the flue-cleaner; and Fig. 8, an end view, 25 partly in section, of the same.

The letter *W* represents a building having a smoke-stack, *B*, which contains the several flues *B'*, as shown in Fig. 2. Each of these flues is connected with the stoves *S'* or open 30 fire-places in one of the stories of the building by stove-pipes *b*. The flues *B'* are connected at their bottom to a funnel, *E*, and this funnel is connected with the flue-cleaner *A* by a hose, *E'*. The communication between flues *B'* and funnel *E* may be shut off by slides or 35 damper-plates *D*, located within the funnel *E*.

The flue-cleaner *A* consists of a cylindrical body or shell, *A'*, preferably mounted upon wheels and connected with an air pump or pumps, *H*. These pumps are designed to extract the air from the shell *A'*, so that the latter in turn extracts by suction the air and soot from the flues *B'*. The pipe *E'* contains a valve, *G*, which is closed while the air is extracted from the shell *A'*, and is opened when 40 the suction is to take place from the flue.

45 Within the shell *A'* there is contained a fine-wire-gauze drum, *A''*, open at the front, and there having an annular flange, *n*, which connects it to the shell *A'*. This drum receives the 50 soot from hose *E'* and prevents it from clogging the mouth of the air-pump. The rear end of the drum *A''* is closed by a perforated head, *a*, attached to the movable cover *m* of the main shell *A'*. If the soot is to be removed from 55 the perforated drum *A''*, its head *a*, together with the cover *m*, is withdrawn to gain access to the interior of the drum *A''*.

I claim as my invention—

60 The combination of shell *A'* with wire-gauze drum *A''*, flange *n*, pipe *E'*, valve *G*, and air-pump *H*, substantially as specified.

In testimony whereof I have signed my name to this specification in the presence of two subscribing witnesses. .

CARL FRIEDRICH WILHELM DOEHRING.
